(57) **CLAIM**

The ornamental design for a mobile phone case, as shown and
described.

DESCRIPTION

FIG. 1 is a perspective view of a mobile phone case.

FIG. 2 is a front elevation view thereof.

FIG. 3 is a rear elevation view thereof.

FIG. 4 is a top plan view thereof.

FIG. 5 is a bottom plan view thereof.

FIG. 6 is a right side elevation view thereof. A left side
elevation view is a mirror image of the right side elevation
view.

FIG. 7 is a right side view wherein the lid is extended.

FIG. 8 is a cross-sectional view taken along the line 8-8 in
FIG. 4; and,

FIG. 9 is a cross-sectional view taken along the line 9-9 in
FIG. 4.
